US0D1062866S

(12) **United States Design Patent** (10) **Patent No.:** **US D1,062,866 S**
(45) **Date of Patent:** **** Feb. 18, 2025**

(54) **PEN TIP CASE**

(71) Applicant: **Shenzhen Mirai Create Technologies Co., Ltd.**, Shenzhen (CN)

(72) Inventor: **Xiaochun Wang**, Shenzhen (CN)

(73) Assignee: **Shenzhen Mirai Create Technologies Co., Ltd.**, Shenzhen (CN)

(**) Term: **15 Years**

(21) Appl. No.: **29/871,806**

(22) Filed: **Feb. 28, 2023**

(30) **Foreign Application Priority Data**

Oct. 14, 2022 (CN) 202230677971.5

(51) **LOC (15) Cl.** **19-06**

(52) **U.S. Cl.**

USPC **D19/81**

(58) **Field of Classification Search**

USPC D14/411, 431, 480.3, 223, 243; D19/66, D19/81, 101, 111, 115, 117, 121, 122, D19/130, 139, 163, 164, 166, 167, 168, D19/169, 170, 171, 173, 174, 175, 177, D19/178, 179, 183, 186, 190, 192, 194, D19/195, 196, 197, 199, 202, 203, 204, D19/901, 902, 906, 914, 916, 924, 929, D19/932, 934, 123, 126, 158, 135; D28/7, 9, 76, 77, 86, 88, 89; D27/101, D27/146, 162, 163; D24/113; D26/37, D26/38; D20/23; D8/104; D3/220, 206; D9/452, 453, 437, 529; D10/66; D13/108

(57) **CLAIM**

The ornamental design for a pen tip case, as shown and described.

DESCRIPTION

FIG. 1 is a front, right and top perspective view of a pen tip case, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is a perspective view shown in disassembled state thereof.

The broken lines shown in the drawings illustrate portions of the pen tip case that form no part of the claimed design.

1 Claim, 9 Drawing Sheets
